UNITED STATES PATENT OFFICE.

PETER E. LORENZEN, OF NEW YORK, N. Y.

CHIMNEY-COWL.

No. 839,163.

Specification of Letters Patent.

Patented Dec. 25, 1906.

Application filed April 25, 1906. Serial No. 313,694.

To all whom it may concern:

Be it known that I, PETER E. LORENZEN, a citizen of the United States, residing in Mariner's Harbor, in the county of Richmond and State of New York, have invented certain new and useful Improvements in Chimney-Cowls, of which the following is a specification.

This invention relates to an improvement in chimney-cowls for preventing the smoking of chimneys and producing an effective draft in the chimney, whatever be the direction of the wind.

The invention consists of a chimney-cowl which comprises the novel features of construction and combinations of parts to be hereinafter described and claimed.

In the accompanying drawings, Figure 1 represents a side elevation of my improved chimney-cowl. Fig. 2 is a vertical transverse section through the same on line 2 2, Fig. 1. Fig. 3 is a bottom view of Fig. 1; and Fig. 4 is a horizontal section on line 4 4, Fig. 2.

Similar letters of reference indicate corresponding parts in the different figures of the drawings.

Referring to the drawings, *a* represents a rectangular casing which is provided at its bottom with a pipe *a'*, which is inserted into the chimney, so as to give a firm support for the cowl. The casing *a* is open at its top and provided with upward casing-stays *b*, on which is supported a hood *d*, which prevents the ingress of rain into the casing and permits the outlet of smoke in every direction, according to the direction of the wind.

In the side walls are arranged horizontal openings *o*, of semicircular shape, which extend with their straight ends nearly across the side walls of the casing. Into said semicircular or segmental openings *o* are inserted laterally-curved scoop-shaped and upwardly and inwardly inclined deflecting-plates *e*, which project to the outside of the casing to a less extent than to the inside of the same, said deflecting-plates being attached at the ends by rivets or otherwise to the side walls of the casing and soldered intermediately of their length to the inwardly-extending integral flanges *e'* at the lower curved edges of the segmental openings *o*. The plates *e* taper toward their upper inner ends, as shown, and abut at their side edges against the corners

of the segmental openings. The cowl shown in Fig. 1 is provided with two scoop-shaped deflecting-plates on each side; but it is obvious that a greater number may be arranged, according to the size of the cowl.

The purpose of the scoop-shaped deflecting-plates is to permit the wind, whatever its direction, to strike against the surface of the same, so as to gather up all the steam and discharge at the inner smaller end of the deflecting-plates to the interior of the casing, the air being simultaneously deflected in upward direction, so as to create a suction on the chimney and carry the smoke in upward direction and out on that side which is opposite to the ingoing side of the wind. As the deflecting-plates gather the wind they change the direction of the same according to the inclination of the scoop-shaped deflecting-plates. The wind then strikes against the lower surface of the opposite deflecting-plates, by which the same is again deflected in upward direction and leaves at the upward end of the casing below the hood. Whatever be the direction of the wind, the action of the same on the smoke will be the same—that is to say, an upward motion is imparted to the same toward the upward end of the cowl, while sufficient suction is exerted on the chimney to impart a good draft in the same and prevent smoking.

Having thus described my invention, I claim as new and desire to secure by Letters Patent—

A chimney-cowl comprising a rectangular casing having semicircular openings in the side walls thereof, the curved edges of said openings being lowermost and provided with inwardly-disposed integral flanges, and laterally-curved deflecting-plates supported intermediately of their length on said flanges and abutting at their side edges against the corners of said openings, said plates being inclined upwardly and inwardly and tapered toward their upper inner ends.

In testimony that I claim the foregoing as my invention I have signed my name in presence of two subscribing witnesses.

PETER E. LORENZEN.
